(57) **CLAIM**

I claim the ornamental design for a seat, as shown and described.

DESCRIPTION

FIG. 1 is a perspective view of a seat showing the claimed design.

FIG. 2 is a front view of the seat of FIG. 1.

FIG. 3 is a rear view of the seat of FIG. 1.

FIG. 4 is a first side view of the seat of FIG. 1.

FIG. 5 is a second side view of the seat of FIG. 1; and, FIG. 6 is a top view of the seat of FIG. 1.

The broken lines shown in the drawings illustrate portions of the seat that form no part of the claimed design.

1 Claim, 6 Drawing Sheets
